UNITED STATES PATENT OFFICE

JAMES WHITELEY, OF NORTH TONAWANDA, NEW YORK

DRIVING MECHANISM FOR AMUSEMENT APPARATUS

Application filed April 6, 1928. Serial No. 268,035.

This invention relates to driving mechanism of a type designed and adapted specially for use in rotating amusement apparatus, although the invention may be usefully applied to other purposes.

An object of the invention is to provide an improved driving or propelling mechanism for imparting rotary movements to a rotary amusement apparatus and which may be mounted upon the rotary part of the amusement apparatus or be mounted in a stationary position, as desired.

Another object of the invention is to provide a driving or propelling mechanism for an amusement apparatus comprising an endless track engaged by propelling wheels, whereby either the track and the support therefor or the propelling wheels and the support therefor may be rotated, as desired.

Other objects will appear from the following description, reference being made to the accompanying drawings in which

Fig. 1 is a plan view of a portion of an amusement apparatus embodying the present invention.

Fig. 2 is an enlarged plan view of the propelling wheels, portions of the supporting frame and drive shaft being in section.

Fig. 3 is an outer side elevation.

Fig. 4 is a vertical cross sectional view approximately on the line 4-4 of Fig. 3.

Fig. 5 is a side elevation of an adjustable support for the stationary frame.

Fig. 6 is a vertical sectional view on the line 6-6 of Fig. 5.

The driving or propelling mechanism herein shown is an improvement upon the driving or propelling mechanism disclosed in my application for patent for amusement apparatus, filed December 24, 1927, Serial No. 242,322. In the present instance, the invention is not restricted to an amusement apparatus in which the propelling mechanism is mounted and carried by the part rotatively driven thereby. The propelling mechanism obviously may be mounted on a stationary support if desired.

In the specific embodiment of the invention shown the central frame mast 1 is mounted on a stationary support 2. A hub 3 is ro-

tated about or with the mast 1, as desired. From this hub 3 a number of pairs of angle bars 4 extend radially and have their outer ends rigidly connected by angle bars 5, thus providing a strong frame. The machine also comprises a circular track composed of an angle bar 6 having one flange extending horizontally and the other flange extending vertically. This track is concentric with the mast 1. Each pair of angle bars 4, or selected pairs of said bars 4, has a wheel or roller 7 operating upon horizontal flange of the track 6. Thus, if the frame comprising the bars 4 is rotative said frame is supported by the rollers 7 on the stationary track 6. But it is apparent that the frame comprising the angle bars 4 may be stationary and the track 6 may be rotative, in which latter case said track will be supported on the rollers 7.

A motor 8 is mounted on a platform 9 supported by angle bars 4, and this motor drives the propelling wheels which cooperate with the track 6 in the same way, whether said track be rotative or whether the frame supporting the motor is rotative. The shaft 10 of the motor 8 has on its outer end a beveled gear 11 (Fig. 4) meshing with the beveled gear 12 on the upper end of a shaft 13, the lower end of which shaft has a gear 14 rigid thereto.

A channel bar 15 is supported between a pair of the bars 4, preferably parallel with the adjacent angle bar 5. A supporting frame plate 16 is attached to the channel bar 15 and the adjacent angle bar 5, said plates constituting supports for the propelling wheels which are driven by the gear wheel 14. The plates 16 support a pair of parallel shafts 17, on each of which a tubular shaft 18 is mounted for longitudinal sliding movements between the plates 16. A pair of frame members 19 are mounted on the tubular shafts 18, one of said frame members 19 being rigid with both of said tubular shafts 18, and the other of said frame members being slidable on said tubular shafts toward and away from the adjacent frame member 19. A rod 20 extends through both of the frame members 19 parallel with the shafts 17. An arcuate spring 21 has its ends bear-

ing against one of the frame members 19 and its intermediate portion curving outwardly (Fig. 2). This spring is preferably composed of a number of leaves, as shown. The rod 20 passes through said spring and has a threaded end on which a nut 22 is screwed. Thus the spring 21 and the rod 20 cooperates to actuate the frames 19 toward each other, but the spring 21 will yield to permit the frames to move apart.

The slideable frame 19 supports a pair of vertical spindles 24, on each of which a propelling wheel 25 is mounted for operation against one side of the vertical flange of the track 6 (Fig. 4). The frame member 19 that is rigid on the tubular shafts 18 supports a pair of vertical spindles 26 having propelling wheels 27 attached thereto and arranged to operate against the opposite side of the vertical flange of the track 6 from the wheels 25. The upper end of each of these spindles 26 has a gear wheel 28 attached thereto, and said gear wheels 28 mesh with and are driven by the gear wheel 14. Thus, it will be seen that both wheels 28 are rotated in the same direction and that these driving wheels 25 and 27 automatically adjust themselves to any irregularities in the curvature or thickness of the track 6. It is further obvious that if the supporting frame of the driving mechanism be stationary the track 6 will be rotated, but if the track 6 be stationary the supporting frame for the driving mechanism will be rotated. Sufficient rigidity of the supporting frame for the driving devices may be obtained by use of strengthening bars 29 connecting intermediate portions of the channel bar 15 with the adjacent angle bar 5.

The adjustable support for the stationary part of the amusement apparatus is shown in Figs. 5 and 6, the same comprising a pair of spaced angle bars 30 arranged to rest upon the ground or floor and from which links 31 form pivotal connection with radial frame bars 32 respectively. These radial frame bars 32 may be the same as the radial frame bars 4 in a construction in which the frame of the bars 4 is stationary; or, they may be in connection with the track 6 when said track is stationarily supported. The lower ends of links 33 are pivotally mounted on the same bolt 34 whereby the ends of the links 31 are pivoted to the angle bars 30. The upper ends of the links 33 are connected by a pivot bolt 35 extending transversely under the lower flanges of the angle bars 32. The bolt 35 passes through the eye of a bolt 36 which extends upwardly between the angle bars 32 and through a plate or washer 37 seated on the upper sides of the angle bars 32. A nut 38 screwed on the threaded end of the eye bolt 36 is adjustable to hold the upper ends of the links 33 in any desired relationship to the links 31 by clamping the plate or washer 37

into engagement with the bars 32 so that said bars 32 are clamped between the bolt 35 and said washer or plate 37. When this clamping engagement is obtained spreading of the upper ends of the links 33 from the upper ends of the links 31 is prevented. Thus, by adjusting the upper ends of the links 33 toward or away from the upper ends of the links 31, the height at which the bars 32 are supported may be varied in order to obtain a level condition of the entire frame of which the bars 32 form a part.

In operation the motor 8 is started, thereby rotating the shaft 10 from which the gear 14 is driven. This gear 14, meshing with both gears 28, rotates said gear 28 in the same direction thereby rotating the propelling wheels 27 which are held in clamping engagement with the track 6, whether said track be stationary or rotative. Obviously, if the frame on which the motor 8 is mounted be held stationary and if the track 6 is rotative, said track will be rotated about the mast 1. And, if the track 6 be rigid and stationary and the frame on which the motor 8 is mounted be rotative about the mast 1, said frame on which the motor 8 is mounted will be rotated, because of the cooperative engagement of the rollers 27 and the rollers 25 with opposite sides of the track 6.

It is possible that the track 6 may become bent or otherwise out of perfect curvature and, to compensate for such irregularity, the supports 19 for the respective pairs of rollers 25 and 27 may be moved relatively and they may also move simultaneously in the same or opposite directions. By means of the rod 20 and spring 21 the rollers 25 are clamped against one side of the track 6 and the rollers 27 are held clamped against the opposite side of said track 6 with sufficient pressure to obtain the desired operation of the machine.

I am aware that the machine may be varied within equivalent limits without departure from the nature and principle thereof. I do not restrict myself unessentially, but what I claim and desire to secure by Letters Patent is:—

1. In an amusement apparatus, a support, a pair of parallel shafts mounted in said support, a tubular shaft mounted for sliding movements on each of said first shafts, a frame rigidly supported by said tubular shafts, a wheel rotatively supported by said frame, a frame mounted for sliding movements on said tubular shaft, a wheel rotatively supported by said second frame, a track, means for holding said wheels in position to clamp said track between them, and mechanism for rotating one of said wheels.

2. In an amusement apparatus, a support, a pair of parallel shafts mounted in said support, a tubular shaft mounted for sliding movements on each of said first shafts, a frame rigidly supported by said tubular

shafts, a pair of wheels rotatively supported by said frame, a frame mounted for sliding movements on said tubular shafts, a pair of wheels rotatively supported by said second frame, a track extending between said pairs of wheels, a device for holding said wheels in clamping engagement with said track, and mechanism for rotating another pair of said wheels.

10 3. In an amusement apparatus, a rigid supporting frame, a pair of frames mounted in said supporting frame for sliding movements toward and away from each other, rollers supported by said sliding frames respectively, a rod connecting said sliding frames, a spring on said rod for moving each of said sliding frames in accordance with the sliding movements of the other, mechanism for rotating said rollers that are supported by 15 one of said frames, and a track clampingly engaged between the rollers supported by 20 said respective sliding frames.

4. In an amusement apparatus, a supporting frame, a pair of frames mounted in said 25 supporting frame, means for supporting said pair of frames in said supporting frame for sliding movements toward and away from each other, a wheel supported by each frame of said pair of frames, a rod connecting said 30 pair of frames, a spring supported by said rod and cooperating therewith to move each of said pair of frames in accordance with the sliding movements of the other, and a track clampingly engaged between said wheels.

35 5. In an amusement apparatus, a support, a pair of shafts mounted for sliding movements in said support, a frame rigidly supported by said shafts, a wheel rotatively supported by said frame, a sliding frame mounted 40 for sliding movements on said shafts, a wheel rotatively supported by said sliding frame, a track extending between said wheels, a rod connecting said two frames, a spring mounted on said rod and cooperating therewith to actuate said two frames toward each 45 other, and mechanism for rotating one of said wheels.

JAMES WHITELEY.
